CLAIM

The ornamental design for a gear hanger as shown and described.

DESCRIPTION

FIG. 1 is a perspective view, showing top, left and front of the gear hanger;

FIG. 2 is a top plan view;

FIG. 3 is a right side elevation view;

FIG. 4 is a bottom plan view;

FIG. 5 is a front elevation view;

FIG. 6 is a rear elevation view; and,

FIG. 7 is an environmental perspective view, showing top, right and front of the gear hanger.

The broken lines in FIG. 7 are for the purpose of depicting the environment and form no part of the claimed design.
